UNITED STATES PATENT OFFICE.

WILLIAM M. MURPHY AND JOHN J. REDNER, OF NEW YORK, N. Y.; SAID MURPHY
ASSIGNOR TO ALEXANDER ALEXANDER, OF NEW YORK, N. Y.

DESIGN FOR A FLY-TRAP.

44,344.

Specification for Design.

Patented July 15, 1913.

Application filed April 17, 1913. Serial No. 761,851. Term of patent 14 years.

To all whom it may concern:

Be it known that we, WILLIAM M. MURPHY and JOHN J. REDNER, citizens of the United States, residing in the city, county, and State of New York, have invented a new, original, and ornamental Design for Fly-Traps, of which the following is a specification, reference being had to the accompanying drawings, forming part thereof.

Figure 1 is a top view showing our new design; Fig. 2 is a front elevation thereof,

assuming the lowest part of Fig. 1 to be the front of the device, and Fig. 3 is a side elevation of Fig. 2.

We claim:

The ornamental design for a fly trap as shown.

WILLIAM M. MURPHY.
JOHN J. REDNER.

Witnesses:

SEWARD DAVIS,
OLIVER WILLIAMS.
